DESIGN FOR A CASE FOR CIGARETTES, JEWELRY, POWDER, AND THE LIKE

August Most and Joseph Fogel, Brooklyn, N. Y.

Application October 26, 1939, Serial No. 37,870

Term of patent 7 years

To all whom it may concern:

Be it known that we, August Most and Joseph Fogel, both citizens of the United States and residents of the city of New York (Borough of Brooklyn), county of Kings, and State of New York, have invented the new, original, and ornamental Design for a Case for Cigarettes, Jewelry, Powder, and the like, of which the following is a specification, reference being had to the accompanying drawing, forming part thereof, in which—

Fig. 1 is a perspective view of a case for cigarettes, jewelry, powder, and the like embodying our design;

Fig. 2 is a top plan view of the case; and
Fig. 3 is a front elevational view of the case.

The dominant feature of the design resides in the provision of the dial-like member on the cover of the case in the manner shown.

We claim:

The ornamental design for a case for cigarettes, jewelry, powder, and the like, as shown and described.

AUGUST MOST.
JOSEPH FOGEL.
